REVERSIBLE LIFEBOAT OR RAFT

Harold Augustus Gaskin, London, England

Application September 1, 1943, Serial No. 500,766
In Great Britain August 12, 1942

2 Claims. (Cl. 9—3)

This invention relates to a reversible lifeboat or raft of the type described in the specifications of Letters Patent Nos. 1,241,367 and 1,730,363 and has for its object to enable greater speed to be attained.

With this object the construction of the improved reversible lifeboat or raft is similar to that described in specification No. 1,730,363 but watertight compartments are arranged at the stem and stern and extend up to the level of the top of the coaming and both of the decks have their ends curving away from one another up to the tops of said watertight compartments, that is to say, the curves of that deck which, for the time being, is uppermost lead to the tops of the watertight compartments.

In addition it is desirable that the tops of the watertight compartments at the stem and stern should rise from their junctions with the curved parts of the decks to said stem and stern respectively and that an internal combustion engine of the horizontally opposed cylinder type should be disposed between decks for driving a propeller arranged in a suitable space between or surrounded by watertight compartments at the stern, said propeller being driven by a Cardan shaft with means whereby the inclination of said Cardan shaft to the crankshaft of the engine may be varied according to which deck of the lifeboat or raft is, for the time being, uppermost.

The lifeboat or raft may also be built with an external belt of buoyancy tanks symmetrically disposed above and below its median horizontal plane.

The accompanying drawings illustrate one form of lifeboat constructed in accordance with this invention, Figure 1 being a longitudinal section on a median vertical plane of the boat; Figure 2 is a corresponding plan view, the upper half of the figure being in elevation, and the lower half in section; Figure 3 is a side elevation; Figure 4 is an elevation from the stern and Figure 5 is a transverse midship section of the boat.

The structure comprises a pair of main side walls 11, 11 (Figs. 2 and 5) extending from the stem post 12 (Figs. 1, 2 and 3) of the boat to the stern thereof and converging towards one another at each end; a normally upper deck 14 (Figs. 1, 2 and 5) and a normally lower deck 15 separated from one another by a space 16 (Figs. 1 and 5) constituting, in the main, a central buoyancy chamber of such depth that the temporarily upper deck remains above the normal surface level of the water outside the boat when

the latter is afloat; transverse bulkheads 17 and 18 towards the ends, serving to separate the corresponding end spaces 19 and 20 from the remainder of the interior of the boat; closures 21 and 22 for the upper and lower sides of said end spaces 19 and 20; pairs of longitudinal seats or shelves 23, 23 (Figs. 1 and 2) projecting inwards from the respective main side walls 11, 11, each such seat or shelf extending lengthwise between the transverse bulkheads 17 and 18, and pairs of lateral inner walls 25, 25 (Figs. 2 and 5) spaced apart from the respective main side walls 11, 11 of the boat and extending lengthwise substantially parallel to one another between said transverse bulkheads so as to bound the decks 14 and 15 laterally, said lateral inner walls extending depthwise between the longitudinal seats or shelves 23, 23 in the respective sections of the boat. That space at each side of the boat which is bounded by the main side wall 11, the adjacent lateral inner wall 25, the longitudinal seat or shelf 23 and the transverse bulkheads 17 and 18, thus constitutes a lateral buoyancy chamber 26, which extends throughout substantially the entire depth of the boat structure.

The two lateral buoyancy chambers 26, 26 and the central buoyancy chamber 16 serve to house a plurality of hermetically-sealed air-tanks, formed of sheet metal, which are shaped to fit the chambers and are adapted to maintain the buoyancy of the boat practically unimpaired in the event of the structure of the boat being so injured as to allow water to gain admittance to the interior. These air-tanks are indicated in the drawings in dot-and-dash lines.

The stern compartment 19 houses watertight buoyancy tanks also shown in dot-and-dash lines in the drawings.

27 are vertical tubes connecting together apertures in the respective decks 14 and 15 (Figs. 1 and 5) and fitted with valves of known type adapted, on the one hand, to permit the escape of air from within whichever well of the boat happens to be submerged, and, on the other hand, to permit any water to drain from the then upper well of the boat.

It will be observed from Figure 1 that both decks 14 and 15 extend lengthwise the entire distance between the transverse bulkheads 17 and 18, and, whilst flat at the central parts of their lengths they slope gradually at each end lengthwise away from one another so as to terminate at each end, at the level of the adjacent edges of the closures 21 and 22, which latter slope upwards further to the stem and stern so

that the end spaces 19 and 20 extend up to the level of the top of the coaming or gunwale 28 forming an extension of the main side wall 11 and extending throughout the entire length of the boat between the closures 21 and 22. As shown in Figure 5 the coamings or gunwales 28 slope upwardly and inwardly.

30 are thwart in the normally upper and lower sections of the boat and 33, 33 are central keel-boards (Figs. 1 and 5).

The end spaces 19 and 20 of the boat may be fitted with water-tight cases of metal for containing bread and water, radio equipment or other stores, suitable hatches (not shown) affording access to these cases from both wells of the boat. All the usual fittings of a sea-going open boat may be provided, but are omitted from the drawings as being well understood.

At the stern end of the buoyancy chamber 16 between the decks 14 and 15 (Figs. 1 and 5) there is mounted an internal combustion engine 37 having horizontally opposed cylinders, the shaft 38 of which passes through a suitable water-tight packing 39 in the transverse bulkhead 17 and is connected by a universal joint 40 with a propeller shaft 41 the after end of which is rotatably and slidably mounted in a bearing block 42 pivoted to a nut 43 on a vertical screwed shaft 44 carried by bearings 45, 45 (Figs. 1, 2 and 3). On the shaft 44 are bevel wheels 46, 46 which mesh with bevel wheels 47, 47 on shafts 48, 48 (Fig. 1) which extend forwardly, through the transverse bulkhead 17 into the buoyancy chamber 16 where they are provided with hand wheels 49, 49, the arrangement being such that by turning the appropriate hand wheel (if necessary) the position of the propeller shaft 41 may be reversed to bring a propeller 50 on said shaft below water level. 51, 51 are water-tight hatches in the decks 14, 15 to give access to the engine 37 and the hand wheels 49, 49, and 52 is a guard for the vertical shaft 44 (Fig. 1).

The main side walls 11, 11 are cut away somewhat above and below the median horizontal plane of the boat to admit water to that part of the end space 19 in which the propeller 50 is operative, and it will be seen that the water-tight cases in the end space 19 are shaped to leave sufficient room for the raising and lowering of the propeller shaft 41 and are provided with tubes 53 therethrough to give passage to the shafts 48, 48.

As shown in Figures 2 and 5 additional buoyancy chambers 54 are formed outside the main side walls 11, 11 by rounded subsidiary or outer walls 55, 55 and horizontal partitions 56, 56. Here again, water-tight buoyancy tanks are indicated in dot-and-dash lines.

It is to be observed that as compared with the reversible lifeboat or raft described and illustrated in specification No. 1,730,363 the improved reversible lifeboat or raft is symmetrical about its median horizontal plane, and the arrangement of the decks makes for greater speed.

I claim:

1. A reversible boat of the general type wherein, in effect two open boats are so united bottom-

to-bottom as to constitute conjointly a single structure capable of floating either way upwards; the structure comprising in its depth two sections constituting respectively the normally upper or erect section and the normally lower or inverted section, separated from one another by a space constituting a central buoyancy chamber of such depth that the temporarily upper deck remains above the normal surface level of water outside the boat when the latter is afloat, each of which sections, when upturned, presenting an open well for the accommodation of passengers, means for permitting the escape of air from within whichever well of the boat happens to be submerged and for draining water from the then erect well, watertight tanks disposed in compartments arranged at the stem and stern of the boat and extending up to the level of tops of the wells, the bottoms or decks of said wells curving away from one another and from said central buoyancy chamber up to the tops of said compartments, an internal combustion engine disposed between the curved parts of said bottoms or decks at the stern end of the boat, a propeller arranged in a space at the stern end of the boat and surrounded by the watertight tanks in said compartments, a Cardan shaft connecting said propeller with said engine, and means for varying the inclination of the Cardan shaft to the crank-shaft of said engine.

2. A reversible boat of the general type wherein, in effect, two open boats are so united bottom-to-bottom as to constitute conjointly a single structure capable of floating either way upward; the structure comprising in its depth two sections constituting respectively the normally upper or erect section and the normally lower or inverted section, separated from one another by a space constituting a central buoyancy chamber of such depth that the temporarily upper deck remains above the normal surface level of water outside the boat when the latter is afloat, each of which sections, when upturned, presenting an open well for the accommodation passengers, means for permitting the escape of air from within whichever well of the boat happens to be submerged and for draining water from the then erect well, watertight tanks disposed in compartments arranged at the stem and stern of the boat and extending up to the level of tops of the wells, the bottoms or decks of said wells curving away from one another and from said central buoyancy chamber up to the upper parts of said compartments, said compartments having tops which rise upwards from their junctions with the bottoms or decks of the wells to the stem and stern of the boat, respectively, an internal combustion engine disposed between the curved parts of said bottoms or decks at the stern end of the boat, a propeller arranged in a space at the stern end of the boat and surrounded by the watertight tanks in said compartments, a Cardan shaft connecting said propeller with said engine, and means for varying the inclination of the Cardan shaft to the crankshaft of said engine.

HAROLD AUGUSTUS GASKIN.
